UNITED STATES PATENT OFFICE

HENRY RESCH, OF BAYONNE, NEW JERSEY, ASSIGNOR TO UNDERWOOD ELLIOTT FISHER COMPANY, OF NEW YORK, N. Y., A CORPORATION OF DELAWARE

TYPEWRITING MACHINE

Application filed November 19, 1926. Serial No. 149,339.

This invention relates to an improvement in typewriting machines, and more especially to tabulating mechanism whereby the typewriter-carriage, which holds a work-sheet divided into zones and subdivided into columns, can be tabulated to any column or subdivision thereof in each zone, or from a column in one zone to any selected column or subdivision thereof in an adjacent zone.

10 In the embodiment shown, a set of tabulating keys is used to control the jump movements of the carriage. These keys, herein-after referred to as column-keys, are marked with designations for the respective columns within each zone of the work-sheet. Depression of a column-key will project a column-stop into the path of movement of a zone-stop adjustable on the carriage with respect to a zone on the work-sheet, and the column-stop will operate a carriage-release mechanism to release the carriage to move freely from the right to the left side of the machine until the movement is arrested by the zone-stop striking the projected column-stop.

15 The utility of the foregoing sequence of operations is apparent when considered in connection with the tabulation of the carriage of a typewriting machine in accordance with the bill-form or work-sheet illustrated. In this connection, and assuming that the carriage is at line-starting position, then by depressing a selected one of the column-keys, the carriage will be tabulated to the column in the first zone, as designated by the selected key. A second depression of the same key will tabulate the carriage to a corresponding column in the second zone, and so on. When the carriage is tabulated to any selected column except the last column in any zone, further tabulation to any other selected column within the zone is accomplished by depressing the key marked with the designation for the selected column.

20 A feature of the present invention resides in the provision of a special column-key, which may be arranged beyond one end of the set of column-keys. When the special column-key is depressed, a key-lever is operated to lift a plunger, which operates the carriage-release mechanism, shown and described in

the patent to J. C. McLaughlin, dated April 26, 1910, No. 956,144, and also operates an additional swingable stop, one end of which is provided with a finger, which, when swung upwardly, is projected across the path of movement of the zone-stops. The swingable stop has a limited amount of endwise movement, and moves with the carriage when struck by a zone-stop. A shock-absorbing device, which may be an ordinary retractile spring, is connected to the swingable stop and to a fixed part of the machine, and is effective for restraining the movement of the additional stop to an extent sufficient for absorbing the shock incident to arresting the movement of the carriage. The finger is set for a distance far in advance of the set of column-stops, and is therefore effective when moved into contact with the column-stop housing for increasing the range of the tabulating mechanism to the extent of the distance between the finger and the next adjacent column-stop. In the present form of the invention, this distance is about the same as the distance between the respective column-stops or as the width of one of the columns, so that the special or additional stop permits the use of zones, on the work-sheet or bill-form illustrated, wider than the set of column-stops.

25 Another feature of this invention relates to means for adjusting the position of the special stop relatively to the standard parts of the machine, to the end that the device may be easily fitted to any standard machine having a decimal tabulating stop mechanism. This adjustment may include an eccentric disk rotatably mounted on a fixed stud which serves also as a means for binding the disk in its set position.

30 Other features and advantages will hereinafter appear.

In the accompanying drawings,

35 Figure 1 is a perspective view showing the invention applied to a typewriting machine having a decimal tabulating mechanism.

Figure 3 is a cross-sectional view through line 3—3 of Figure 2.

Figure 4 is a plan view showing the operating connection between the special tabulating stop and the tabulating plunger of lowest denominational order.

Figure 5 is a diagrammatic view showing the special stop elevated for arresting the carriage.

10 Figure 6 is a diagrammatic view showing how the special stop clears the carriage when the operating key is released.

This invention is illustrated as applied to an Underwood typewriting machine having a decimal tabulating stop mechanism. The machine has a traveling carriage provided at the rear thereof with a cross-bar 10, having teeth 11 for receiving adjustable zone-stops 12. The carriage is also provided with 15 a platen 13 rotatably mounted on a shaft 14, which platen, together with the feed-rolls 15, serves as a means for holding and line-feeding a work-sheet 16.

The work-sheet 16, selected to illustrate one 20 use of this invention, is provided with three zones of corresponding width and respectively indicated by 17, 18 and 19. Each of said zones is subdivided into four columns of corresponding width. When the character of 25 the billing in connection with the use of said sheet is such that the use of the first column, designated by the term "Part" in the respective zones, is not needed, the tabulation of the carriage may be effected by depressing the column-keys 24, which are respectively marked with the designations A, B, C, to correspond with the designations used for the columns in each of the zones.

Column-stops 20 are mounted in a housing 30 21 which is fast to the frame of the machine. The housing carries at the top thereof a pair of slotted plates 22 which are fast thereto by means of screws 23. These plates serve as a means for guiding the upper ends 35 of the stops 20 which are moved upwardly by depressing their respective keys 24, which are mounted at the ends of key-levers 25, pivotally mounted on a cross-bar 26.

The usual way of operating this machine, 40 50 when all of the columns are to be used in one or more of the zones, is first to tabulate the carriage by depressing the special key 27 marked "Part", which releases the carriage to tabulate to the "Part" column in the first zone of the work-sheet. The "A" key 24 adjacent the "Part" key is next depressed and the carriage is moved to a position to receive typing on the "A" column; and so on by operating the "B" and "C" keys. In case 55 60 the entire first zone is to be jumped, the special key 27 is depressed for a second time and the carriage is automatically positioned for typing on the "Part" column of the second zone.

65 The key-lever 28 of the special key 27 oper-

ates a plunger 20', which is made shorter than the column-stops 20. The plunger or push-bar 20' is provided with an extension 29 which engages in a slot 30 and rocks a special or additional stop 31 pivotally mounted on a stud 32 carried by the front plate 22. The stop 31 is bent at one end thereof forming an interposing finger 33 which is disposed far in advance of the set of column-stops 20 and is movable into the path of the zone-stops when the key 27 is depressed. The operation of the stop 31 is illustrated in Figures 2, 5 and 6. Figure 2 shows the stop in its normal position, while Figure 5 shows the stop after the carriage, the movement of which is arrested by the finger 33. It will be noted, by referring to Figure 5, that the stop has been moved along with the carriage against the tension of a spring 34 into contact with housing 21, and the zone-stop 12 is spaced from the adjacent column-stop to an extent corresponding to the width of the first column in each zone. After releasing the key 27, the stop 31 is moved downwardly away from the tabulating stop and the spring 34 restores the plate again to its normal position as shown in Figure 6, with the finger 33 thereof arranged to the right of zone-stop 12. In order to relieve the special stop 31 from undue strain when struck by a zone-stop, it is proposed to make the spring 34 very heavy so that the same may act as a shock-absorber. The spring is mounted between the spring studs 37 and 38 respectively secured to the stop 31 and to one of the plates 22. The stop 31 is arranged so that, when moved in the direction of the carriage, the finger 33 will strike the housing 21 as shown in Figure 5. This relieves the stud 32 from strain, since the shock is taken up by the housing.

The amount of engagement between the finger 33 and the tabulating stop may be adjusted by means of an eccentric disk 35 which passes through an elongated slot 36 in the stop 31. This disk may be positioned by loosening the stud 32 and by rotating the same therearound. Then the stud is tightened to lock the disk in its set position.

Intermediate keys 39 are disposed between the column-keys A—B, B—C, and beyond the column-key C. These intermediate keys 39 are used for tabulating the carriage to select subdivisions of the columns A, B and C. Key-levers 40 are mounted on cross-bar 26, and are secured to the keys 39 and arranged for projecting intermediate stops 41, which are arranged in housing 21; the arrangement of column and intermediate stops is such that said stops provide a set of selected stops arranged at letter-space intervals.

Variations may be resorted to within the scope of the invention, and portions of the improvements may be used without others.

Having thus described my invention, I claim:

1. In a typewriting machine and in a tabulating mechanism for typing upon a work-sheet having a series of typing zones, with each zone subdivided into a series of columns, the typewriting machine including a carriage having zone-determining stops movable therewith, and the tabulating mechanism having a series of vertically-disposed denominational stops mounted within a stationary frame and operative to engage an advancing zone-stop to selectively arrest the carriage to permit typing within any column of the zone predetermined by the zone-stop, the combination of means for arresting the carriage in advance of a typing zone-position on the work-sheet prior to selectively tabulating the carriage denominational 70 into the zone to relieve the denominational stops from the carriage-impact, said means including an auxiliary key at the keyboard of the machine to operate a key-lever, a vertical push-bar liftable by the key-lever, and an auxiliary stop mounted upon a fulcrum stationary with the stop-frame and swingable about said fulcrum into the path of an advancing zone-determining stop to arrest the carriage, the fulcrum being changeable relatively to the auxiliary stop to vary the stop-position when 75 the carriage is arrested. 80
2. In a typewriting machine and in a tabulating mechanism for typing upon a work-sheet having a series of typing zones, with each zone subdivided into a series of columns, the typewriting machine including a carriage having zone-determining stops movable therewith, and the tabulating mechanism having a series of vertically-disposed denominational stops mounted within a stationary frame and operative to engage an advancing zone-stop to selectively arrest the carriage to permit typing within any column of the zone predetermined by the zone-stop, the combination of means for arresting the carriage in advance of a typing zone-position on the work-sheet prior to selectively tabulating the carriage denominational 90 into the zone to relieve the denominational stops from the carriage-impact, said means including an auxiliary key at the keyboard of the machine to operate a key-lever, a vertical push-bar liftable by the key-lever, and an auxiliary stop mounted upon a fulcrum stationary with the stop-frame and swingable about said fulcrum into the path of an advancing zone-determining stop to arrest the carriage, the fulcrum being changeable relatively to the auxiliary stop to vary the stop-position when 95 the carriage is arrested. 100
3. In a typewriting machine and in a tabulating mechanism for typing upon a work-sheet having a series of typing zones, with each zone subdivided into a series of columns, the typewriting machine including a carriage having zone-determining stops movable therewith, and the tabulating mechanism having a series of vertically-disposed denominational stops mounted within a stationary frame and operative to engage an advancing zone-stop to selectively arrest the carriage to permit typing within any column of the zone predetermined by the zone-stop, the combination of means for arresting the carriage in advance of a typing zone-position on the work-sheet prior to selectively tabulating the carriage denominational 110 into the zone to relieve the denominational stops from the carriage-impact, said means including an auxiliary key at the keyboard of the machine to operate a key-lever, a vertical push-bar liftable by the key-lever, and an auxiliary stop mounted upon a fulcrum stationary with the stop-frame and swingable about the fulcrum by the push-bar into the path of an advancing zone-determining stop, said auxiliary stop having an elongated slot to receive the fulcrum and a spring to hold said stop spring-pressed towards the advancing zone-stop to 115 the limit of the slot, said zone-stop being effective to carry the auxiliary stop along the stationary fulcrum and be retarded by the tension of the spring to cushion the arrest of the carriage by the auxiliary stop. 120
4. In a typewriting machine and in a tabulating mechanism for typing upon a work-sheet having a series of typing zones, with each zone subdivided into a series of columns, the typewriting machine including a carriage releasable to a driving carriage tension and having zone-determining stops movable therewith, and the tabulating mechanism having a series of vertically-disposed denominational stops mounted within a sta- 125
5. In a typewriting machine and in a tabulating mechanism for typing upon a work-sheet having a series of typing zones, with each zone subdivided into a series of columns, the typewriting machine including a carriage releasable to a driving carriage tension and having zone-determining stops movable therewith, and the tabulating mechanism having a series of vertically-disposed denominational stops mounted within a sta- 130

- tionary frame and operative to release the carriage and engage an advancing zone-stop to selectively arrest the carriage to type within any column of the zone predetermined by 5 the zone-stop, the combination of means co-operative with each zone-determining stop and operative to release and arrest the carriage at the initial position of a work-sheet zone including a special key at the keyboard 10 of the machine, a horizontal key-lever of the first order, a vertical push-bar liftable by the key-lever to release the carriage, and a horizontally-disposed auxiliary stop firmly mounted upon the stationary frame to be 15 lifted by the push-bar into the horizontal path of the zone-determining stops to arrest the driven carriage in advance of the denominational stop-positions to relieve said stops of the carriage-impact. 20 6. In a typewriting machine and in a tabulating mechanism for typing upon a work-sheet having a series of vertical zones, with each zone subdivided into a series of columns, the typewriting machine including a power- 25 driven releasable carriage having zone-determining stops, and the tabulating mechanism having a plurality of denominational stops within a stationary vertical frame and operative to release the carriage and engage an 30 advancing zone-stop for selectively arresting the carriage to type within any column of the zone predetermined by the setting of the zone-stops, the combination of an auxiliary zone-determining key independently 35 operative to release the carriage, and an auxiliary stop controlled by said key, said auxiliary stop fulcrumed upon said stationary frame and swingable from a normal horizontal position into the horizontal path of 40 the zone-stops by a carriage-releasing connection with said key, to arrest the carriage. 7. In a typewriting machine and in a tabulating mechanism for typing upon a work-sheet having a series of vertical zones, with 45 each zone subdivided into a series of columns, the typewriting machine including a power-driven releasable carriage having zone-determining stops, and the tabulating mechanism having a plurality of denominational stops 50 within a stationary vertical frame and operative to release the carriage and engage an advancing zone-stop for selectively arresting the carriage to type within any column of the zone predetermined by the setting of the 55 zone-stops, the combination of an auxiliary zone-determining key independently operative to release the carriage, and an auxiliary stop controlled by said key, said auxiliary stop fulcrumed upon said stationary frame 60 and swingable from a normal horizontal position into the horizontal path of the zone-stops by a carriage-releasing connection with said key, to arrest the carriage, said auxiliary stop also effective, in swinging out of engagement with the zone-stop, to release the zone- 65 positioned carriage, to avoid interference between the two stops when the auxiliary stop is immediately brought into position to arrest the next zone-stop for zone-skipping the carriage and work-sheet. 70 HENRY RESCH. 75 80 85 90 95 100 105 110 115 120 125 130
